(57) **CLAIM**

I claim the ornamental design for the wristband mounted television, as shown and described.

DESCRIPTION

FIG. 1 is a front view of the wristband mounted television.

FIG. 2 is a rear view of the claimed design.

FIG. 3 is a left end view of the claimed design.

FIG. 4 is a right end view of the claimed design.

FIG. 5 is a top view of the claimed design.

FIG. 6 is a bottom view of the claimed design; and,

FIG. 7 is an isometric view of the claimed design.
